UNITED STATES PATENT OFFICE.

BENNO VOM EIGEN, OF NEWARK, NEW JERSEY, ASSIGNOR TO AUG. GOERTZ & CO., A CORPORATION OF NEW JERSEY.

CLOSURE FOR COIN-REPOSITORIES.

1,108,349.

Specification of Letters Patent. Patented Aug. 25, 1914.

Application filed June 22, 1912. Serial No. 705,220.

To all whom it may concern:

Be it known that I, BENNO VOM EIGEN, a citizen of the United States, residing at Newark, in the county of Essex and State of New Jersey, have invented certain new and useful Improvements in Closures for Coin-Repositories; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in coin-repositories or banks; and, the invention relates, more particularly to a novel closing means, provided with a key-operated mechanism, for closing the open end of the shell or casing of the bank.

The present invention has for its principal object to provide a novel construction of closing device or means for the open end-portion of the sheet-metal shell or case of the bank, and a novel means for producing the proper registration of the closing device or means within the said open end-portion of the bank, such means acting as a stop or stops to prevent the closure from being inserted in place too far within the shell or case of the bank, whereby the closure can be readily secured in its locked relation within the said shell or case.

The invention has for its further object to provide in connection with the open end-portion of the shell or case of the bank and its closure, a novel means adapted to be engaged by and co-operating with said closure for preventing the spreading of the sides of sheet-metal shell or case; and, furthermore, to prevent the forcible displacement or removal of the closure from within the open end-portion of the shell or case of the bank for the surreptitious extraction of the contents of the bank.

Other objects of this invention not at this time more particularly enumerated will be clearly understood from the following detailed description of the present invention.

With the various objects of the present invention in view, the said invention consists, primarily, in the novel arrangements and combinations of the several devices and parts, as well as in the details of the construction of the same, all of which will be

more fully described in the following specification, and then finally embodied in the clauses of the claim which are appended to and which form an essential part of this specification.

The invention is clearly illustrated in the accompanying drawings, in which:

Figure 1 is a side elevation and Fig. 2 a bottom view of a coin-repository or bank embodying the principles of the present invention. Fig. 3 is a central longitudinal vertical section, and Fig. 4 is a central transverse vertical section of the parts of the coin-repository or bank, both of said views being made on an enlarged scale. Fig. 5 is a horizontal section taken on line 5-5 in Fig. 3, looking in the direction of the arrow α ; Fig. 6 is a detail longitudinal vertical sectional representation of the lower open end-portion of the shell or case of the bank, and a side elevation of the closure in position and of one of the holding or retaining devices with which the said closure co-operates to prevent the spreading of the sides of the sheet-metal shell or case of the bank; and Fig. 7 is a perspective view of one of the said holding or retaining devices.

Similar characters of reference are employed in all of the above described views, to indicate corresponding parts.

Referring now to the several figures of the drawings, the reference-character 1 indicates a suitably shaped sheet-metal shell or case, preferably of an oval configuration, comprising the longitudinally extending sides 2 and the rounded connecting ends 3, the shell or case having a closed top 4 and an open lower end-portion 5. The closed top 4 is usually provided with upwardly extending handle-posts, as 6, with which may be suitably connected a handle 7 of any desired shape and configuration. In one of its rounded ends 3, the said shell or case is provided with a suitable coin-receiving slot 8, and within the said shell or case, in close proximity to said slot is a coin-receiving and depositing device, as 9, which may be of any suitable construction. Within the said open end-portion 5 of the shell or case is removably disposed a suitably formed closure for closing the said open end 5. This closure in the present instance consists, essentially, of a lower face-plate 10, having an upwardly extending marginal flange 11, which conforms to and is adapted to be fitted in the lower open end-portion of the

- shell or case 1. The marginal flange 11 of the said plate 10 is also provided with upwardly extending retaining lugs 12 and upwardly extending projectional elements, as 5 13, formed with an opening 14 between them. The said face-plate 10 is provided with an opening 15 in which is operatively disposed a key-receiving barrel 16 of any suitably formed locking mechanism 17.
- 10 The reference-character 18 indicates a suitable back-plate which is formed with a downwardly extending marginal flange 19, said flange 19 being embraced by the previously-mentioned marginal flange 11 of the 15 face-plate 10, and the two plates 10 and 18 being suitably secured together by means of the previously mentioned retaining or holding lugs 12 which are bent over upon the said back-plate 18, as will be clearly evident 20 from an inspection of Figs. 3, 5 and 6 of the drawings. Within the said shell or case 2, being suitably secured to the inner surface- 25 portions of the connecting ends 3, preferably by means of rivets 20, are plates 21, each plate 21 being provided with a lug-like member 22 extending at right angles from the lower end-portion of each plate 21, and the said lug-like members 22 forming suitable stops within the open portion of the 30 shell or case 1, which prevents the previously-mentioned closure from being inserted too far within the shell or case, and thus brings the lock-mechanism contained within the said chambered closure into its proper 35 and operative relation within the said shell or case 1, as will be clearly evident from an inspection of Figs. 3, 4 and 5 of the drawings.
- The previously mentioned back-plate 18 is 40 provided with a pair of oppositely disposed openings or slots 23 in which are movably arranged and from which project the catch- 45 portions or members 24 of the locking bolts of the key-operated lock-mechanism 17. Suitably secured by means of rivets 25, or 50 otherwise, to the inner faces of the longitudinally extending sides 2 of the shell or case 1 are a pair of plate-like members or elements 26, each member or element 26 being 55 provided at its lower end-portion with inwardly extending and angularly arranged engaging members 27. The previously mentioned catch-portions or members 24, when the lock-containing closure is inserted in the 60 open end portion of the shell or case 1, are readily forced over and sprung into holding engagement with the said angularly arranged engaging members 27, whereby the said closure is retained in its locked relation 65 within the said lower open end-portion of the shell or case 1, but can be readily removed therefrom, as will be clearly evident when the lock-mechanism 17 is operated by

means of a suitable key, to bring the said catch-members 24 into their disengaged relation with the angularly extending holding or retaining members 27. As will be seen more especially from an inspection of Fig. 7 of the drawings, the angularly arranged holding or retaining members 27 have their 70 end-portions 28 extending in opposite directions beyond the marginal edge-portions 29 of the plate-like members or elements 26, so as to provide a pair of marginal holding edge-portions 30, behind which the previously mentioned projectional elements 13, when the closure has been placed in the open end-portion of the shell or case 1, are slipped into retaining engagement with the said end-portions 28, and thereby positively prevent any spreading or bulging out of the longitudinally extending sides 2 of the shell or case 1, as will be clearly understood from an inspection of Figs. 3, 5, 6 and 7 of the drawings.

85 Of course, I am aware that some changes may be made in the general arrangements and combinations of the various devices and parts, as well as in the details of the construction of the same, without departing 90 from the scope of the present invention as defined in the appended claim. Hence, I do not limit my invention to the exact arrangements and combinations of the various devices and parts as set forth in the foregoing 95 specification, nor do I confine myself to the exact details of the construction of the said parts as illustrated in the accompanying drawings.

100 I claim:

A coin-repository comprising a shell or case having a closed top and an open bottom, a chambered closure within said open bottom, a key-operated lock-mechanism within said closure, catch-portions connected with said closure and extending therefrom, plate-like elements within said shell or case, means for securing said plate-like elements in position, an angular engaging member connected with each plate-like 110 element with which said catch-portions are adapted to be brought into locked engagement, and upwardly extending projectional elements connected with said closure also adapted to be brought into holding engagement with said angular engaging members 115 to prevent spreading of the walls of the shell or case when the closure is in position within said shell or case.

120 In testimony, that I claim the invention set forth above I have hereunto set my hand, this 20th day of June, 1912.

BENNO vom EIGEN.
